Atty's.

UNITED STATES PATENT OFFICE.

FRANK GUNN FARNHAM, OF HONESDALE, PENNSYLVANIA.

NAME-PLATE FOR UMBRELLAS.

1,246,077.

Specification of Letters Patent. Patented Nov. 13, 1917.

Application filed October 9, 1916. Serial No. 124,580.

To all whom it may concern:

Be it known that I, FRANK G. FARNHAM, a citizen of the United States, and resident of Honesdale, Pennsylvania, have invented 5 certain new and useful Improvements in Name-Plates for Umbrellas, of which the following is a specification.

My present invention relates to improvements in means for attaching the owner's 10 name to an umbrella stick and its object is to provide means by which the name may be applied in an economical, expeditious, and ornamental manner and the name itself may be formed by quickly assembling and 15 applying the proper letter carrying elements and which can be cheaply produced and kept in stock in large numbers in department and other stores.

My invention includes the novel features 20 of construction and combination of parts hereinafter described and particularly defined by the appended claims.

Several embodiments of my invention are shown in the accompanying drawings, in 25 which,

Figure 1 is a side view also of a tubular metal sleeve adapted to fit the stick of an umbrella and carrying the name forming elements.

30 Fig. 2 is a section of a metal tube cut off to form one of the character forming elements, but here shown in blank.

Fig. 3 is a period bearing ring.

Fig. 4 is one of the character bearing 35 rings.

Fig. 5 is a perspective of Fig. 2.

Fig. 6 is a cross section of the umbrella stick, the tubular sleeve, and a character bearing element.

40 Fig. 7 is a view, partly in side elevation and partly in longitudinal section, showing a sufficient portion of an umbrella to illustrate the application of the invention.

Fig. 8 is a similar view showing the application of my invention to the tip of an umbrella or parasol.

Fig. 9 is a longitudinal section of a metal sleeve showing a flange on the handle end which acts as a retainer to the character 50 bearing elements after assembling the name.

Fig. 10 is a side view of the devices attached to an umbrella handle.

Fig. 11 is a side view of the stick end of an umbrella handle.

55 Fig. 12 represents a part of the grip end of an umbrella handle.

Fig. 13 is a side elevation of Fig. 2 partly mounted with a few of the character bearing elements in position.

Fig. 14 is a sectional side elevation of an 60 umbrella handle formed by assembling the parts shown in Fig. 12 and 13.

Fig. 15 is a view of a modified form of ring adapted for name and address.

In these drawings 1 designates a section 65 of a thin metal tubular sleeve of a size adapted to slip over and snugly fit the umbrella rod or stick. This tube has a longitudinal slot 2 extending from one end nearly its full length and a cross cut 2' to permit 70 of expansion. A part of the sleeve about one-eighth of an inch long is not slotted and between this and the slotted portion is an annular rib or bead 3 extending around the sleeve which acts as a rear stop. 75

From a thin metal tube, preferably of brass, are cut the character bearing rings, represented by Figs. 2 to 5 inclusive. The inner diameter of these rings agrees with the outside diameter of the sleeve. Fig. 2 80 represents a side view of a spacing ring, Fig. 3 a period bearing ring, and Fig. 4 a letter or other character ring. In Fig. 3, 5' indicates the period set a little below the center line, and in Fig. 4 is shown the letter 85 "H", indicated at 6' as representative of any one of the letters of the alphabet and which may be in relief or intaglio, but the former is preferable. Preferably directly opposite the location of letter character a cross section of the ring is depressed, forming an inside bead or rib 4' which is adapted to fit and slide along the slot 2 of the sleeve 1. All blanks, period rings and character bearing rings are provided with similar interior 90 ribs which fit said slot 2. These ribs act as guides and prevent the rings from turning when assembled, thus retaining the letters in alignment when forming the name. This rib 4' is shallow and in depth corresponds 95 to the thickness of metal wall of the sleeve 1. In Fig. 6 I have shown a cross section enlarged of an umbrella stick or rod 10, a sleeve 1, a letter ring 6, a raised letter 6' and the depressed rib 4'. The sleeve 1 has a 100 narrow cross cut 2' to allow for expansion after assembling the name, and when said sleeve is driven onto the umbrella stick the bead 8, Fig. 2, acts as a stop and prevents the letter rings from passing farther along 105 the sleeve.

The part 1' is about one-eighth of an inch

long and not only acts as a binder fitting the stick rather closely but provides a surface for prick punching as indicated at 1", thus preventing further movement of the sleeve along the stick. In Fig. 9 I have shown a longitudinal section of a sleeve with a flange 1", which holds the rings in position after assembling the name, which is necessary when filling orders by mail. In 10 all sleeves I prefer to let the free end project beyond the last letter ring assembled thereon, about one-sixty-fourth of an inch, which corresponds to the thickness of the sleeve wall. This projecting part when 15 crimped back against the assembled rings holds them firmly in place, see 1", Figs. 8 and 9.

Fig. 7 is a view partly in side elevation and partly in longitudinal section, showing 20 a sufficient portion of an umbrella to illustrate the application of the invention and in which 10 is the stick or rod, 11 the lower stop, 12 the runner, 12' the stretcher connection, 13 stretchers, 14 the handle, 15 ferrule. A sleeve is shown mounted on the rod with a name F. G. Farnham partly appearing thereon.

A portion is cut away showing portions of the rod, sleeve, and rings, 4-4 being 30 blanks, 1" a prick punch mark, 1" the flange. In Fig. 8 a shorter name, W. B. Hull, with the usual number of blanks and period rings are shown assembled onto a shorter sleeve and placed on the tip of an 35 umbrella. In this method of applying it is not necessary to remove the handle 14, which is required in Fig. 7.

The letter rings indicated in Fig. 9 are cut off from thin metal tubing, the letters 40 being formed by means of suitable dies either before or after cutting off. Period rings are also provided, (Fig. 3) and spreader rings, (Fig. 2) the former for separating the initials of the name, the latter for filling up any unused space. In forming the flanged sleeves, (Fig. 1) I may make them sufficiently long to take a name of thirteen or more letters with two initials and two period rings, for shorter names the 50 extra space may be occupied by filler rings. Different lengths of sleeves may be provided, however, to correspond to the number of letters in a name.

Where a great number of names are to be 55 fitted to umbrella sticks, for instance in a large department store, fonts of letter rings of each letter of the alphabet, with period and spreader rings could be kept in stock for forming names of from three to fifteen 60 letters with initials and also the symbol "&" for use in forming the name of a company.

It will be understood that the great majority of umbrellas have their handles attached at the factory where made. Some, 65 however, have no handles, the purchaser se-

lecting his handle from the store stock, it then being attached by the salesman. Others have detachable and interchangeable handles. My invention applies in either class, but in the first named the handle must first 70 be removed, which is easily and quickly done by means of a small vise, a hammer, and a piece of wood. In replacing the handle, a cement of some kind is used, generally shellac varnish being employed for this 75 purpose.

While in Figs. 7 and 8, I have shown all of the rings of uniform width, it is evident that the blanks and period rings may be made narrower, thus allowing more room 80 on the sleeve for the name. I have found upon investigating the letters in hundreds of names that the average, including two initials, is ten. This gives ample room for the longest name, thirteen letters, including 85 two initials.

I estimate that three sleeves only of different lengths will be necessary. For instance, the name J. A. Dix, five letters, two period rings, and two filler rings; the name 90 W. B. Hull, six letters, two period rings, and one filler ring, and the name C. H. Smith, six letters, two period rings, and no fillers. This comprises one set of names, all on the same sleeve. The next longer sleeve 95 will take names of eight, nine and ten letters, including two initials, and the third sleeve, still longer, will take eleven, twelve, and thirteen letters, including two initial letter rings, two period rings, and no fillers. 100

It is evident that an umbrella handle, Fig. 10, is one of the main important units necessary to make a complete article, and, as such, I have shown the invention applied to the handle. The drawing shows a bend 105 to form the grip, 14, and the handle may be straight, with or without a knob, and in cross section round, square, or octagon. In other than a round shape the character rings would conform thereto, but the best results 110 are obtained by rabbeting that part of the handle, 14', to which the sleeve is to be fitted. In this case, the name is first assembled on the sleeve, and then forced onto the rabbeted part 14'. A ferrule 15, is then 115 fitted to the unoccupied part, holding the sleeve, with its accompanying elements, in position.

While I have shown the stick part of the handle, 14' as rabbeted, it is not always necessary to rabbet this part. The stick end of the handle varies in diameter from one-half inch to three-fourths of an inch and are turned true, in which case the sleeve may be made to fit over this part without rabbeting. The sleeves and character rings would be made to fit the various sizes. I estimate that it will require three sizes of sleeves to fit the different diameters of handles, with its accompanying elements. Material, fin- 120 125 130

ish, etc. would conform to that portion of the specifications relating to same. Practically the only difference between the application of the invention to the handle is that of size, the various elements being larger. For instance, the character rings would be a trifle wider, five-thirty-seconds of an inch, instead of one-eighth of an inch, and larger in diameter to fit a larger sleeve. In this construction the handles would be fitted to the sleeves at the handle factories, where they make handles only, and then fitted and mounted by the retailer.

In the form shown in Figs. 10 and 11 it will be understood that the groove to receive the beads of the rings is formed directly in the rabbeted portion of the handle as indicated at c^2 .

Instead of applying the rings to the rabbeted portion I may form the handle in two parts as shown in Figs. 13 and 14.

In these figures 20 designates the handle having a rabbeted portion on which is applied a sleeve 21 and 22 designates a wooden cylinder or supplemental handle portion in which is provided a ferrule 23 and into which the umbrella rod 10 is fitted or driven. The cylinder 22 is designed to have the rings threaded thereon in name forming order and thereafter the cylinder is inserted in the sleeve 21 and secured in place. The cylinder 22 is provided with a groove 22^a to receive the beads of the rings which are clamped between the end of ferrule 23 and the end of sleeve 21.

When it is desired to have the rings bear both the name and address of the owner I prefer to form them in the manner shown in Fig. 15 in which they are provided with alternate reversely arranged wide narrow portions, the wide portions of one set of rings coming uppermost and, when assembled forming the owner's name, and the wide portions of the other set lying between the narrow portions of the first set and bearing the address. This arrangement enables me to apply the name and address without unduly lengthening the aggregate rings.

The invention is shown and described as applying in particular to the stick and handle of an umbrella. It may however, be ap-

plied for instance to such articles as canes, whip handles, fish rods, fountain pens, etc., with equal facility.

55

What I claim is:—

1. Name applying means for umbrellas and the like comprising a cylindrical part adapted to be carried by the umbrella, and a plurality of independent character carrying and spacing rings threaded on said cylindrical part, said part and said rings having tongue and groove connection to insure alinement.

2. As an article of manufacture, a carrying tube of sheet metal having a longitudinal groove, and a plurality of independent character carrying rings threaded on said tube and having inwardly struck portions forming ribs to engage said groove.

3. As an article of manufacture a carrying tube of sheet metal having a longitudinal groove extending from one end thereof, an annular stop flange at the inner end of said tube, and a plurality of independent character carrying rings threaded on said tube and abutting each other and said stop flange, said rings having inwardly projected ribs engaging said groove.

4. As an article of manufacture, a carrying tube of sheet metal having a longitudinal slot extending from one end partway the length of the tube, there being a transverse slot at the inner end of said longitudinal slot, and a plurality of character forming rings having ribs engaging said longitudinal slot.

5. In combination with an umbrella stick or handle, a carrying tube applied to said stick, having an annular flange at one end and a plurality of independent character bearing rings non-rotatably held on said tube, and confined between said flange and a part of the stick or handle.

6. In combination with a cylindrical part on an umbrella, a plurality of character bearing rings threaded thereon, said rings having alternate wide and narrow portions with characters on the wide portions.

FRANK GUNN FARNHAM.
